HAND OPERATED PRINTING PRESS

Carl Edward Carlsen, New York, N. Y.

Application December 7, 1936, Serial No. 114,585

8 Claims. (Cl. 101—298)

This invention relates to new and useful improvements in a hand operated printing press.

This invention has for an object the construction of a printing press which is characterized by the fact that it has a stationary printing bed base supporting a pair of spaced L-shaped arms in side alignment with each other and pivotally mounted thereon, which in turn pivotally support a handle associated with a type holding form pivotally depending therefrom at a point offset from the pivot support of the handle.

Still further the invention contemplates the provision of an inverted U-shaped arm pivotally mounted at one end on said bed base and having its other end horizontally extended and connected with said type holding form.

Still further the invention proposes the provision of a hanging attachment mounted on the latter end of the U-shaped arm and cooperative with said handle and said type holding form.

Another one of the objects of this invention is to arrange said U-shaped arm at an inclined position from the vertical and extending away from said L-shaped arms.

Still further the invention proposes the association of a table extension with the printing press and other details generally desirable or necessary with a printing machine.

Another one of the objects of this invention is to arrange the U-shaped arm of two sections joined at the junction of the arms of the U-shape and adapted to be connected together in various positions to control the relative supporting of the type holding form.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:—

Fig. 1 is a plan view of a hand operated printing press constructed according to this invention.

Fig. 2 is a sectional view taken on the line 2—2 of Fig. 1.

Fig. 3 is a sectional view taken on the line 3—3 of Fig. 1.

Fig. 4 is an end elevational view looking from the left hand end in the direction of the line 4—4 of Fig. 2.

Fig. 5 is an end view looking from the right hand end in the direction of the line 5—5 of Fig. 2.

Fig. 6 is a plan view of the printing press in an open position.

Fig. 7 is a sectional view taken on the line 7—7 of Fig. 6.

Fig. 8 is a sectional view taken on the line 8—8 of Fig. 6.

Fig. 9 is a fragmentary view similar to a portion of Fig. 2 and illustrating the central portion of a U-shaped arm constructed according to a modification of the invention.

The hand operated printing press, according to this invention, includes a stationary printing bed base 10. A pair of spaced L-shaped arms 11 are arranged in side alignment with each other and are pivotally mounted by pintles 12 at their lower ends upon said base 10. A handle 13 is pivotally supported between the upper ends of the L-shaped arms 11 by a spindle 14. A type holding form 15 pivotally depends from the handle 13 at a point offset from the pivot support 14 of the handle. An inverted U-shaped arm 16 is pivotally mounted at one end 16^a by a pintle 17 to the base 10. This arm 16' has its other end 16^b extended horizontally and flexibly or resiliently connected with the type holding form 15. The U-shaped arm 16 is inclined slightly rearwards from the vertical direction away from the L-shaped arms 11.

The printing bed base 10 is provided with a removable sheet covering element 19 which is held in position by several clips or clamps 20. Thus, if the element 19 becomes soiled it may be replaced. An extension table 21 is provided with several projecting fingers 22 which are adapted to engage into receiving openings in the base 10 for supporting the extension table 21. This extension table is adapted to support papers which are to be printed or which have already been printed. The base 10 is provided with lugs 23 which support the pintle 12 on the ends of which the L-shaped levers 11 are mounted.

The L-shaped levers 11 have their short bottom arms 11^a extending normally slightly upwards from the horizontal direction when the printing press is in its closed position. The vertical arms 11^b extend upwards at an inclination and terminate in tip portions 11^c substantially vertical and normally in the closed position of the printing press located in a vertical plate in the center of the arms 11^a. With this arrangement it is possible to obtain a very great pressure between the type holding form and the printing bed. The L-shaped handles 11 are disposed upon

the outer sides of the printing bed 10 as clearly shown in Fig. 1.

The handle 13 has a lug portion 13^a which extends at right angles from one side and which support is pivotally supported by the pintle 14. The handle 13 is formed with projecting rear end portions 13^b forming bearings for rods 25. These rods are resiliently urged in one direction by springs 26 coaxially thereon and acting 5 against the bearings at one of their ends and heads 27 upon the outer ends of the rods. The inner ends of the rods 25 are pivotally connected by a pintle 28 with a bearing housing 29. These bearing housings have spaced bearing supports 10 receiving shafts 30 from inking rollers 31. These inking rollers are urged by the springs 26' against an ink supply disc 33. This ink supply disc is rotatively supported by a stud 34 upon the arm 16^b.

15 There are a plurality of radial lugs 37 arranged upon the rear face of the ink disc 33 and are engageable with a pawl 38 mounted upon an arcuate bracket 39, projecting from the handle 13. This pintle 38 is pivotally supported by a 20 pintle 40 intermediate of its ends and its rear end is provided with lug portions 38^a disposed on opposite sides of the bracket 39 to limit its pivoting to a small amplitude. The arrangement is such that when the handle 13 is moved to open 25 the printing press—to the position shown in Fig. 8—the pintle 38 will engage against the projections 37 and partially turn the inking disc 33. Thus, for each operation of the press the inking disc is partially turned. On the back stroke of the handle 13 the pintle 38 idles past the projections 37 and so the inking disc is turned in 30 one direction only.

There is a stud 41 which engages through a thick and resilient washer 42, preferably of rubber, and which is firmly mounted upon the type holding form 15. It is this rubber washer 42 which forms the resilient or flexible connection between the type holding form and the arm 16^b of the U-shaped arm 16. This washer 42 allows the type holding form to slightly move in 40 one direction or another so that it engages against the printing bed in a proper flat position. There are a pair of tracks 43 mounted along the sides of the type holding form 15. 45 There are rollers 44 mounted upon the shafts 30 and adapted to run along the tracks 43. These tracks 43 extend at one of their ends to the printing disc 33. They are arranged so that when the handle 13 is moved to the open position the inking rollers 30 are run along the bottom sides of the tracks 43 and pass the printing form 15' which is mounted in the printing holding form 15 and so ink the printing form.

The printing form 15' is removably mounted 50 in position by set screws 45. There are several protective holding fingers 46 which extend beneath the type holding form and in the closed position of the form, extend through grooves 47 in the type holding form. These fingers 46 are 55 mounted upon a shaft 48 which is rotative upon the printing bed and held against the printing bed by springs 48'. These fingers are also equipped with a cam finger 49 cooperative with 60 a cam finger 50 mounted upon the pintle 17 to raise holding fingers 46 when cam finger 50 acts on cam finger 49. The arrangement is such that when the U-shaped arm 16 is pivoted backwards as shown in Fig. 8 the cams 50 and 49 engage 65 each other to wrap the fingers 46. Thus a

sheet of paper may be slipped beneath the fingers.

There are several paper guiding elements 51 and 52 mounted upon the printing bed and on the table extension 21 so that papers fed the printing press may be properly positioned.

The operation of the device is as follows:—

Fig. 2 shows the press in a closed position. To open the press the outer end of the handle 13 is moved upwards. The pivot 26 has a tendency 10 to move about the pivot 14 as a center along the arc AB. But in reality the pivot 26 will not move along this arc because the L-shaped arms 11 are pivotally mounted and recede as the handle 13 is lifted. The free end 16^b of the U-shaped arm 15 must travel in an arc such as the arc CD since it pivots about the pintle 17. As the type holding form 15 is substantially rigidly mounted on the arm 16^b it must move along with the arm 16^b. Consequently, the pintle 26 must travel along 15 the arc AB'. It is possible for the pintle 26 to move along the arc AB' because the L-shaped arms B will pivot downwards along the arc EF. The press thus opens up to a position as shown in Fig. 3. The springs 26' urge the inking rollers 20 18 against the face of the inking disc 33 and then the tracks 43.

To close the printing press the handle 13 is merely moved downwards. The parts then assume 25 positions shown in Fig. 2 and there is a great mechanical advantage for urging the printing form against the printing bed.

In Fig. 9 there is a modified form of the invention in which there is a vertical U-shaped arm 16' very similar to the arm 16 but formed of adjacent sections 16^d and 16^e. These adjacent sections are connected at the center or bent portion of the U-shape. They are connected by several bolts 57. Between the contact ends there are a plurality of shims 58 of different 30 thicknesses. These shims may be removed selectively and replaced as desired for slightly moving together or moving apart the arms 16 and 16^e and so adjusting the relative support of the type holding form 15 to the U-shaped arm 40 16'. It is thus possible to adjust the press to compensate for wear or disintegration of the rubber washer 42 or inability of the rubber washer to hold the type holding form with sufficient 45 flexibility so that it properly engages the printing bed.

While I have illustrated and described the preferred embodiments of my invention, it is to be understood that I do not limit myself to the precise constructions herein disclosed and the right 55 is reserved to all changes and modifications coming within the scope of the invention as defined in the appended claims.

Having thus described my invention, what I claim as new, and desire to secure by United 60 States Letters Patent is:—

1. In a hand operated printing press, a stationary printing bed, a pair of spaced L-shaped arms in side alignment with each other pivotally mounted at their lower ends on said bed, a 65 handle pivotally supported between the upper ends of said L-shaped arms, a type holding form pivotally depending from said handle at a point offset from the pivot support of said handle, an inverted U-shaped arm pivotally mounted 70 at one end on said bed and having its other end horizontally extended and connected with said type holding form, an inking attachment mounted on the latter end of said U-shaped arm and cooperative with said handle and type hold- 75

ing form, and said U-shaped arm being inclined slightly from the vertical direction and away from said L-shaped arms.

2. In a hand operated printing press, a stationary printing bed, a pair of spaced L-shaped arms in side alignment with each other pivotally mounted at their lower ends on said bed, a handle pivotally supported between the upper ends of said L-shaped arms, a type holding form pivotally depending from said handle at a point offset from the pivot support of said handle, an inverted U-shaped arm pivotally mounted at one end on said bed and having its other end horizontally extended and connected with said type holding form, an inking attachment mounted on the latter end of said U-shaped arm and cooperative with said handle and type holding form, and said U-shaped arm being inclined slightly from the vertical direction and away from said L-shaped arms, said L-shaped arms having their bottom arm sections disposed slightly upwards when the printing press is closed and their vertical arms extending upwards at an angle and terminating in the vertical tips disposed in planes at the center of the bottom arm sections.

3. In a hand operated printing press, a stationary printing bed, a pair of spaced L-shaped arms in side alignment with each other pivotally mounted at their lower ends on said bed, a handle pivotally supported between the upper ends of said L-shaped arms, a type holding form pivotally depending from said handle at a point offset from the pivot support of said handle, an inverted U-shaped arm pivotally mounted at one end on said bed and having its other end horizontally extended and connected with said type holding form, an inking attachment mounted on the latter end of said U-shaped arm and cooperative with said handle and type holding form, and said U-shaped arm being inclined slightly from the vertical direction and away from said L-shaped arms, said handle being provided with an offset lug, and it is this lug portion which is pivotally connected with said L-shaped levers.

4. In a hand operated printing press, a stationary printing bed, a pair of spaced L-shaped arms in side alignment with each other pivotally mounted at their lower ends on said bed, a handle pivotally supported between the upper ends of said L-shaped arms, a type holding form pivotally depending from said handle at a point offset from the pivot support of said handle, an inverted U-shaped arm pivotally mounted at one end on said bed and having its other end horizontally extended and connected with said type holding form, an inking attachment mounted on the latter end of said U-shaped arm and cooperative with said handle and type holding form, and said U-shaped arm being inclined slightly from the vertical direction and away from said L-shaped arms, said handle being provided with an offset lug, and it is this lug portion which is pivotally connected with said L-shaped levers, and being disposed substantially in the same plane with the vertical ends of the L-shaped levers when the printing press is closed so as to present a large mechanical advantage to the printing press in the closed position.

5. In a hand operated printing press, a stationary printing bed, a pair of spaced L-shaped arms in side alignment with each other pivotally mounted at their lower ends on said bed, a

handle pivotally supported between the upper ends of said L-shaped arms, a type holding form pivotally depending from said handle at a point offset from the pivot support of said handle, an inverted U-shaped arm pivotally mounted at one end on said bed and having its other end horizontally extended and connected with said type holding form, an inking attachment mounted on the latter end of said U-shaped arm and cooperative with said handle and type holding form, and said U-shaped arm being inclined slightly from the vertical direction and away from said L-shaped arms, said type holding form being slightly resiliently and flexibly connected with the said end of the U-shaped arm.

6. In a hand operated printing press, a stationary printing bed, a pair of spaced L-shaped arms in side alignment with each other pivotally mounted at their lower ends on said bed, a handle pivotally supported between the upper ends of said L-shaped arms, a type holding form pivotally depending from said handle at a point offset from the pivot support of said handle, an inverted U-shaped arm pivotally mounted at one end on said bed and having its other end horizontally extended and connected with said type holding form, an inking attachment mounted on the latter end of said U-shaped arm and cooperative with said handle and type holding form, and said U-shaped arm being inclined slightly from the vertical direction and away from said L-shaped arms, said type holding form being slightly resiliently and flexibly connected with the said end of the U-shaped arm, by reason of a supporting stud mounted on the type holding form and associated with a rubber or other resilient washer in intimate contact with the end of the U-shaped arm.

7. In a hand operated printing press, a stationary printing bed, a pair of spaced L-shaped arms in side alignment with each other pivotally mounted at their lower ends on said bed, a handle pivotally supported between the upper ends of said L-shaped arms, a type holding form pivotally depending from said handle at a point offset from the pivot support of said handle, an inverted U-shaped arm pivotally mounted at one end on said bed and having its other end horizontally extended and connected with said type holding form, an inking attachment mounted on the latter end of said U-shaped arm and cooperative with said handle and type holding form, and said U-shaped arm being inclined slightly from the vertical direction and away from said L-shaped arms, said U-shaped arm being also formed of two sections jointed at the center of the U-shaped arm, and means for connecting these sections at different relative positions to control the relative position of the type holding form with other parts of the printing press.

8. In a hand operated printing press, a stationary printing bed, a pair of spaced L-shaped arms in side alignment with each other pivotally mounted at their lower ends on said bed, a handle pivotally supported between the upper ends of said L-shaped arms, a type holding form pivotally depending from said handle at a point offset from the pivot support of said handle, an inverted U-shaped arm pivotally mounted at one end on said bed and having its other end horizontally extended and connected with said type holding form, an inking attachment mounted on the latter end of said U-shaped arm and cooperative with said handle.

and type holding form; and said U-shaped arm being inclined slightly from the vertical direction and away from said L-shaped arms, said U-shaped arm being also formed of two sections jointed at the center of the U-shaped arm, and means for connecting these sections at dif-

ferent relative positions to control the relative position of the type holding form with other parts of the printing press, the arm sections of said U-shaped arm being separated by removable shims.

CARL EDWARD CARLSEN.
